UNITED STATES PATENT OFFICE.

ALFONSO R. RHEINBERGER, OF ST. PAUL, MINNESOTA.

POLE-LINE LIGHTNING-ARRESTER.

949,130.

Specification of Letters Patent. Patented Feb. 15, 1910.

Application filed October 7, 1908. Serial No. 456,627.

To all whom it may concern:

Be it known that I, ALFONSO R. RHEINBERGER, a citizen of the United States, residing at St. Paul, in the county of Ramsey and State of Minnesota, have invented a new and useful Improvement in Pole-Line Lightning-Arresters, of which the following is a specification.

My invention relates to improvements in lightning arresters and more particularly to a device of its kind which is to be applied to a line wire outside of a building to effectively ground an excessive charge of electric current prior to reaching the instrument or other apparatus protected.

A further object of this invention is to provide a construction which will be simple and inexpensive to manufacture and in which the leaking of the charge around the arrester will be prevented.

The instrument is characterized by the fact, that the device is particularly adapted for use in pole line construction and that the parts are associated with an insulator to which the line is secured and with the pin or bracket upon which said insulator is adapted to be mounted.

In the accompanying drawings forming part of this specification, Figure 1 is a sectional elevation partly in section of my invention showing the parts associated with an insulator and a pin; Fig. 2 is a perspective view of the electrode which is adapted to be connected with ground; Fig. 3 is a perspective view of the electrode which is adapted to be connected with the line conductor, and Fig. 4 is a plan view illustrating the line conductor connected with a pair of insulators which are provided with my improvement, and Fig. 5 is a view of an insulator employing my invention in which a helix is included.

In the drawings, A represents an insulator made of glass or other suitable material and B a pin made of wood or other suitable material upon which said insulator is threaded in the usual manner. The insulator has the usual annular groove 2 in which the line conductor 3 is secured by means of the tie-wire 4 or by any other means desired. The lower portion of the insulator is formed with a petticoat 5 which is adapted to prevent water from coming into contact with the electrodes in the insulator.

C represents the line electrode and D the

ground electrode of the lightning arrester, said parts being seated in the lower end of the insulator and held apart with an air gap 6 between them by means of an intervening shoulder 7. The line electrode C is in the form of a frusto conical shell having two depending and upturned arms 8 and 9 which are secured in the groove 2 in contact with the line conductor 3 and tie-wire 4 thus assisting to support the line electrode in the insulator. Normally the line conductor is held in place upon the insulator before the line conductor is secured thereto, by detents 10 which are formed in the arms 70 and spring into the groove 2 in the insulator.

As shown the pin B is formed with a shoulder 11 between the threaded upper end 12 and the body 13 which is adapted to be mounted upon a cross-arm or bracket in the usual manner. The ground electrode D is in the form of a sleeve which is passed over the threaded upper end of the pin and clamped between the insulator and the shoulder 11 when said insulator is screwed home. A ground conductor 14 in the form of a wire is adapted to be secured between the ground electrode and the shoulder 11 at its upper end and with the ground E at 85 its lower end. The outer surface of the ground electrode tapers toward its upper end thus forming a parallel surface with the inner surface of the line electrode. The line and ground electrodes may be made out of any suitable material desired and the connection between the line conductor and the line electrode and the means for supporting the line electrode in the insulator may be changed and modified as desired within the scope of my invention. In operation all over-charges of atmospheric electricity are dissipated into the ground from the line conductor by passing over the connectors 8 and 9 and jumping across the gap between 100 the line and ground electrodes and thence are conducted into the ground over the ground wire.

As shown in Fig. 5, a second annular groove 15 is formed in the insulator which is adapted to hold the drop or branch 16 leading from the line conductor to the telephone set at a subscriber's station. Interposed between said branch and line conductor is a helix of wire 17 whose function 110 is to offer a high impedance effect to lightning discharges causing them to seek a

course of least resistance across the gap between the electrodes C and D of the lightning arrester and into the ground instead of causing damage to instruments contained 5 in the branch conductor.

In accordance with the patent statutes I have described the principle of operation of my invention together with the apparatus which I now consider to represent the best 10 embodiment thereof but I desire to have it understood that the construction shown is only illustrative and that the invention can be carried out by other means and applied to uses other than those above set forth 15 within the scope of the following claims.

Having described my invention what I claim as new and desire to protect by Letters Patent is:

1. The combination with an insulating pin 20 and an insulator mounted thereon having means for holding a line, a pair of electrodes one being mounted upon the insulator and connected with the line and the other mounted upon the pin and connected with ground, 25 said electrodes being spaced apart to form an air gap across which oscillatory discharges are adapted to jump.

2. The combination with an insulating pin and an insulator mounted thereon having a 30 petticoat and means for holding a line, a pair of electrodes within said insulator and covered by said petticoat one being mounted upon the insulator and connected with the line and the other mounted upon the pin and 35 connected with ground said electrodes being spaced apart to form an air gap across which oscillatory discharges are adapted to jump.

3. The combination with an insulating pin 40 and an insulator mounted thereon having means for holding a line, a pair of electrodes one mounted upon the insulator and having a connector in contact with the line and the other mounted upon the pin and 45 connected with ground, said electrodes being covered by the insulator and spaced apart to form an air gap across which oscillatory discharges are adapted to jump.

4. The combination with an insulating pin 50 having a threaded upper end and a body with an intervening shoulder and an insulator threaded upon the upper end of said pin and having an annular groove for holding a line conductor and a petticoat formed 55 with an inner surface having an annular shoulder, a pair of electrodes in the form of

sleeves, one of larger diameter than the other, said sleeves being held within the insulator with said shoulder on the insulator intervening to hold them spaced apart, the 60 outer sleeve having an arm, extending into the groove of the insulator to hold the outer sleeve in place and the inner sleeve being clamped between the insulator and the shoulder on the pin, for the purposes specified. 65

5. The combination with an insulating pin B and an insulator A mounted thereon having an annular groove 2 in its outer surface for holding a line, a pair of line and ground electrodes C and D inserted in the lower end 70 of the insulator and spaced apart by a shoulder 7 formed on the inner surface of the insulator, said line electrode being formed with a pair of arms extending into the groove on the outer surface of the insulator 75 and said ground electrode being placed upon the pin and adapted to be connected with ground, said electrodes being spaced apart to form an air gap across which oscillatory discharges are adapted to jump. 80

6. A device of the class set forth, comprising, in combination with a main conductor, a branch conductor, a ground conductor, a pin, and an insulator therefor having a petticoat, a pair of electrodes spaced 85 apart in the lower end of said insulator one being mounted upon said pin and connected with said ground conductor and the other mounted upon said insulator and co-operating with one of said main and branch conductors and a helix also co-operating with said main and branch conductors; whereby said petticoat is adapted to shed water from said electrodes, said helix to impede the passage 90 of lightning discharges over the branch conductor and said electrodes to offer a course to dissipate said discharges into the ground. 95

7. The combination with an insulating pin and an insulator mounted thereon, a pair of line and ground electrodes between said insulator and pin, one of said electrodes being mounted on said insulator and the other on said pin, said electrodes being spaced apart to form an air gap across which oscillatory discharges are adapted to jump. 100

In testimony whereof, I have signed my name to this specification, in the presence of two subscribing witnesses.

ALFONSO R. RHEINBERGER.
